UNITED STATES PATENT OFFICE

JOHN K. OSTRANDER, OF PHILADELPHIA, PENNSYLVANIA

CABLE CLAMP

Application filed January 12, 1931, Serial No. 508,307. Renewed May 18, 1933.

This invention relates to improvements in suspension means for high tension electric cables and the like, and relates more particularly to improvements in the clamps whereby the cables are attached to the insulators through which the said cables are suspended from the supporting towers or poles.

One object of the invention is to provide a cable-gripping clamp in which the gripping force is automatically regulated by the weight of that portion of the cable supported by the individual clamp.

Another object of the invention is to provide a cable-supporting clamp of the stated character having an automatic safety feature, in that increase of the load applied to the clamp through the cable to a predetermined maximum results in a partial release of the gripping force of the clamp, permitting longitudinal slippage of the cable through the clamp.

Another object of the invention is to provide a clamp in which any upward movement of the cable in the supported part has the effect of temporarily releasing the grip, for a purpose hereinafter fully set forth.

Still another object of the invention is to provide a cable-gripping clamp having certain desirable self-adjusting characteristics, as hereinafter set forth.

The invention further resides in certain desirable structural features and details hereinafter described and illustrated in the attached drawing, in which:

Figure 1 is an end elevation of a clamp made in accordance with my invention, and

Fig. 2 is a side elevational view of the clamp.

With reference to the drawing, the clamp in a preferred form comprises a pair of arms 1 and 2 joined together at their lower ends by means in the present instance of a pair of bolts 3, 3, said arms being provided with aligned openings 4 and 5, respectively, which receive the trunnions 6 and 7, respectively, of a pair of segmental cable-gripping elements 8 and 9, adapted in assembly and as illustrated in Fig. 1 to engage the opposite sides of a cable 10. From a point above the openings 4 the arms 1 and 2 flare outwardly

away from each other, as indicated at 11, and each arm at its upper extremity is provided with an opening for reception of a pin 12, these pins functioning to secure to each of said arms a pair of links, 13, 13 and 14, 14, respectively. These pairs of links which preferably occupy positions on opposite sides of their respective associated arms 1 and 2 converge upwardly and are pivotally connected through the medium of a pin 15 to a depending arm 16. This arm is adapted to be secured to a bank of insulators which may be supported on or suspended from any suitable supporting structure.

The retaining bolts 3, 3 are more or less free in the arms 1 and 2 to permit a certain limited adjustability of the arms with respect to each other. The construction described thereby produces through the medium of the arms 1 and 2, the bolts 3 and the links 13 and 14 a toggle effect wherein the weight of the cable 10 tends to draw the upper ends of the arms 1 and 2 together and consequently the elements 8 and 9 forcibly against the opposite sides of the cable. The gripping force of the elements 8 and 9 upon the cable, therefore, varies directly with the load applied to the clamp through the cable. It will be noted, however, that the load constituted by the cable 10 has a tendency to cause the upper portions 11 of the arms 1 and 2 to straighten out into the positions illustrated by the broken lines in Fig. 1. By a judicious proportioning of the said arms, it is possible to introduce into the device a critical maximum load-sustaining factor whereby at a given maximum load the said arms 1 and 2 will flex into positions approximately as shown in broken lines. This has the effect of elongating the toggle by increasing the angle at the toggle joint, and thereby correspondingly reduces the toggle action and the effective gripping force of the elements 8 and 9 upon the clamp. When so constructed, the effective grip of the clamp upon the cable will increase in direct ratio with the increase of the load applied through the cable to a predetermined maximum, at which point the gripping force is automatically decreased a predetermined extent, this reduction in the gripping action

being sufficient to permit longitudinal slippage of the cable between the gripping jaws 8 and 9 in the event that the load at opposite sides of the said jaws is unbalanced.

5 As a practical application of this principle, it will be understood that high tension and similar cables are commonly supported on high towers placed at reasonable intervals, and that when one of the transmission lines 10 parts between any two towers, the normally balanced strain upon the adjacent towers is immediately unbalanced. In some instances, these towers are made sufficiently strong to withstand these unbalanced strains, but this 15 involves a relatively high expense in the construction of the towers, and for that reason is undesirable. With the present device, the supporting towers may be built to withstand a predetermined unbalanced strain, and the 20 arms 1 and 2 of the clamp may be so constructed that they will flex under a corresponding load. Under these circumstances, the clamp will retain its normal secure grip upon the cable under all conditions except 25 when the load upon the clamp approaches the maximum sustaining load of the tower, whereupon the clamp will permit slippage of the cable, insuring a sufficient balancing of the load upon the tower to prevent damage 30 to the latter.

In addition to the action described above, the device operates to relieve the towers of some of the shock resulting from the recoil of the loose ends of the cable at opposite sides 35 of a break. The supported cables are necessarily under a considerable tension which when a break occurs results in a heavy recoil of the wire at each side of the break. Where, as has previously been the practice, the cable 40 is gripped rigidly by the clamps, the afore-described reaction is taken up entirely by the adjacent towers which must be built to withstand this sudden heavy unbalanced load. It has been found that the initial recoil of the 45 wires has the effect of actually elevating the wire where it is supported at the adjacent towers. My clamp utilizes this elevation of the cable to temporarily release the clamping grip thereby to permit momentary free longitudinal movement of the cable through the jaws. The initial heavy reaction of the ruptured cable upon the tower is thus relieved. It will be apparent that any lifting force applied to the clamp through the cable will tend 50 to separate the upper ends of the arms 1 and 2 which releases the gripping pressure of the jaws 8 and 9, not sufficiently, however, to entirely disengage the jaws from the cable.

In addition to the automatic safety features 60 described above, my invention provides a device of relative simplicity and low cost of manufacture which at the same time is highly efficient in its intended function. By mounting the clamping jaws upon trunnions as described, the jaws automatically adjust them-

70 selves to the normal position of the cable and thereby avoid undue strains upon the clamp or upon the cable. The invention also affords by simple means an adjustment of the clamp to fit cables of different diameters, this being accomplished by a tightening or loosening of the bolts 3 and by use of clamping jaws 8 and 9 having an internal curvature corresponding to the circumferential dimensions of the particular cable to be supported. 75

There may be modification without departure from the invention.

I claim:

1. A cable clamp comprising a pair of upwardly diverging arms, means for securing 80 the arms together adjacent their lower ends, suspension means connected to said arms and permitting movement of the upper ends of the arms toward each other, and means intermediate the ends of said arms for engaging 85 opposite sides of a cable, the diverging portions of said arms being so constructed and arranged as to flex inwardly when the said load exceeds a predetermined maximum whereby the gripping force of said arms upon 90 the cable is automatically decreased.

2. In a cable-supporting clamp, the combination with a pair of upwardly diverging arms, of a pair of oppositely arranged cable-engaging clamps respectively pivotally 95 mounted in said arms on axes transverse to the direction of the supported cable, means for pivotally connecting the said arms at a point below the said cable-gripping jaws, the upper ends of said arms being adjustably 100 secured to a supporting structure whereby the weight of the cable tends to draw the upper ends of said arms together.

3. A cable clamp comprising a pair of interconnected clamping arms, and means for 105 suspending the arms so that they tend to draw together upon an interposed cable, said arms being constructed to bend under a predetermined abnormal force to decrease the clamping pressure thereof upon the cable. 110

4. In a suspension clamp for cables, the combination with a pair of arms having intermediate the ends thereof opposed cable-gripping jaws, of means for pivotally securing 115 said arms together at a point below said jaws, said arms comprising divergent portions above the jaws, means for suspending the arms from a supporting structure whereby the weight of a supported cable in conjunction with the divergent arms tends to 120 draw the jaws firmly against the cable, and said divergent parts being constructed to bend toward each other under a predetermined abnormal load to thereby decrease the clamping pressure on the cable.

5. In a cable-supporting clamp, the combination with cable-gripping elements, of a toggle suspension for said elements tending to elongate under weight of the cable, said toggle determining the pressure of the grip. 130

ping elements on the cable, and an element of said toggle being displaceable under a predetermined abnormal load to afford an elongation of the toggle partially relieving the 5 gripping force of the clamp upon the cable.

6. A cable-supporting clamp comprising oppositely arranged toggles, means for gripping a cable between said toggles, and means for suspending said toggles, an element of 10 said toggles being displaceable under a predetermined load to effect an elongation of the

toggles relieving a portion of the clamping pressure thereof upon the cable.

7. In a cable clamp, the combination with cable-gripping elements, of means including a cable-supporting member constructed to distort under a predetermined abnormal load for reducing the gripping force on the cable of said elements when the load imposed by the cable on the clamp reaches a predetermined maximum. 70 75
